UNITED STATES PATENT OFFICE.

ALVAN B. BROWN, OF BENTON HARBOR, MICHIGAN.

SPRAYER.

1,097,788.

Specification of Letters Patent. Patented May 26, 1914.

Application filed June 5, 1913. Serial No. 771,881.

To all whom it may concern:

Be it known that I, ALVAN B. BROWN, a citizen of the United States, residing at Benton Harbor, Michigan, have invented 5 certain new and useful Improvements in Sprayers, of which the following is a specification.

This improvement relates to improvements in sprayers.

10 My improved sprayer is especially designed by me for use in spraying fruit trees and the like where the spray is directed by the operator on the ground or on a wagon or spraying machine.

15 The main objects of this invention are to provide an improved sprayer in which the character of the sprayer may be changed at will, which is very effective and at the same time simple and economical in structure, 20 durable in use and not likely to become clogged.

Further objects, and objects relating to structural details will definitely appear from the detailed description to follow.

25 I accomplish the objects of my invention by the devices and means described in the following specification.

The invention is clearly defined and pointed out in the claims.

30 A structure which is a preferred embodiment of my invention is clearly illustrated in the accompanying drawing forming a part of this specification, in which:

Figure I is a detail side elevation of a 35 structure embodying the features of my invention. Fig. II is a detail longitudinal section through the sprayer head. Fig. III is a transverse section on a line corresponding to line 3—3 of Fig. II. Fig. IV is a 40 detail section on a line corresponding to a line 4—4 of Fig. I.

In the drawing similar reference characters refer to similar parts throughout the several views, and the sectional views are 45 taken looking in the direction of the little arrows at the ends of the section lines.

Referring to the drawing the delivery pipe 1 is of suitable size and length for the 50 convenient manipulation of the sprayer, it constituting a handle and being in practice usually about eight feet in length and connected to the source of supply under pressure or to a force pump by means of a flexible pipe tube 2. The pipe 1 is provided

with a valve 3 at its lower end. The sprayer head or body is elbow shaped so that its face or tip 5 is directed laterally. The face or tip member 5 is provided with a threaded flange 6 threaded upon the body. The tip 5 has a central delivery orifice 7. A disk-like plate 8 is arranged within the body, it being supported by the annular shoulder 9. The tip member and plate are supported in a spaced relation by means of a gasket 10 which not only spaces the members to 65 provide the chamber 11, but also seals the joints. The member 8 is provided with delivery passages 12 disposed to deliver at an angle into the chamber 11, which causes the liquid to whirl in the chamber and it 70 is discharged through the orifice 7 in a whirling spray. The member 8 is provided with an inwardly projecting extension 13, having a passage 14 therein alined with the orifice 7. The extension 13 has a flat face 75 15 constituting a valve seat for the valve 16, the valve seat being in a plane substantially at right angles with a longitudinal axis of the pipe 1, which is threaded into the inner end of the nozzle head or body 4, 80 as shown in Fig. II. The valve stem 17 is arranged through the inner end of the body 4 and provided with a packing gland 18. The valve stem 17 is in the form of a rod 85 and is disposed parallel to the pipe 1. The valve stem passes through the guide 19, which also serves as a support for the valve return spring 20, the upper end of the spring being connected with the valve 16 through the washer 21 and cotter pin 22. 90 The valve actuating lever 23 is pivotally mounted on the pipe 1 by means of the clip 24 and is pivotally connected with the valve stem by the pivot 25. When the valve 16 is opened the liquid is admitted directly to 95 the orifice 7, which changes the character of the spray somewhat and delivers it farther from the nozzle.

The arrangement of the valve seat in the manner shown and described enables the 100 disposition of the valve stem parallel to the pipe, so that the stem is reciprocated with little strain or wear on the same or its bearings and packing in the head. This is of decided advantage as efforts have been made 105 to operate valves with the stems disposed at an angle to the pipe, which soon wears the parts so that the liquid escapes and is

thrown into the face of or on to the person of the operator, which is very disagreeable.

My improved sprayer is simple and economical to produce and at the same time is very efficient and durable in use, and is not likely to become clogged.

Having thus described my invention, what I claim as new and desire to secure by Letters Patent is:

1. In a sprayer, the combination with the delivery pipe, of a chambered elbowed nozzle body having an internal annular seat at its outer end, a nozzle tip member with a central delivery orifice, threaded upon said body, a plate arranged in said seat in said body, there being a gasket between said tip and plate whereby the joints are sealed and said plate and tip member are supported in a spaced relation to provide a chamber therebetween, said plate having delivery orifices therein disposed to deliver at an angle into the chamber between said tip member and plate, and being provided with an inward projection having a longitudinal passage therein alined with said delivery orifice of said tip member and provided with a valve seat at its inner end, the plane of the valve seat being at right angles to the longitudinal axis of said delivery pipe, a valve coacting with said seat, a valve stem disposed through the inner end of said body and parallel with said pipe, a guide for said stem mounted on said pipe, a valve actuating lever mounted on said pipe and pivotally connected to said stem, and a return spring for said valve, said stem guide constituting a support for said spring.

2. In a sprayer, the combination with the delivery pipe, of a chambered elbowed nozzle body, a nozzle tip member with a central delivery orifice, a plate supported in a spaced relation from said tip member to provide a chamber therebetween, said plate having delivery orifices therein disposed to deliver at an angle into the chamber between said tip member and plate, and being provided with an inward projection having a longitudinal passage therein alined with said delivery orifice of said tip member and provided with a valve seat at its inner end, said inward projection being disposed at an angle to the longitudinal axis of said delivery pipe, the plane of the valve seat being at right angles to the longitudinal axis of said delivery pipe, a valve coacting with said seat, a valve stem disposed through the inner end of said body and substantially parallel with said pipe, a guide for said stem mounted on said pipe, a valve actuating lever mounted on said pipe, and a return spring for said valve, said stem guide constituting a support for said spring.

3. In a sprayer, the combination with the delivery pipe, of a chambered elbow shaped nozzle body, a nozzle tip member having a delivery orifice, a plate disposed in said body, there being a chamber between said

plate and tip member, said plate having a delivery orifice therein arranged to deliver at an angle into the chamber between said tip member and plate, and being provided with an inward projection having a longitudinal passage therein alined with said delivery orifice of said tip member and with a valve seat at its inner end, the plane of the valve seat being substantially at right angles to the longitudinal axis of said delivery pipe, a valve coacting with said seat, a valve stem disposed through the inner end of said body and substantially parallel with said pipe, a guide for said stem mounted on said pipe, a valve actuating lever mounted on said pipe, and a return spring for said valve, said stem guide constituting a support for said spring.

4. In a sprayer, the combination with the delivery pipe, of a chambered elbow shaped nozzle body, having a delivery orifice directed at an angle to the axis of said delivery pipe, a plate disposed in said body, and provided with an inward projection, having a longitudinal passage therein alined with said delivery orifice and with a valve seat at its inner end, said inward projection being disposed at an angle to the longitudinal axis of said delivery pipe, the plane of the valve seat being substantially at right angles to the longitudinal axis of said delivery pipe, a valve coacting with said seat, and a valve stem disposed through the inner end of said body and substantially parallel with said pipe.

5. In a sprayer, the combination with the delivery pipe, of a chambered nozzle body having a laterally directed delivery orifice, a passage member provided with an inward projection having a longitudinal passage therein alined with said delivery orifice of said nozzle body and with a valve seat at its inner end, the plane of the valve seat being substantially at right angles to the longitudinal axis of said delivery pipe, a valve coacting with said seat, a valve stem disposed through the inner end of said body and substantially parallel with said pipe, a guide for said stem mounted on said pipe, a valve actuating lever mounted on said pipe, and a return spring for said valve, said stem guide constituting a support for said spring.

6. In a sprayer, the combination with the delivery pipe, of a chambered nozzle body, a nozzle tip member having a central delivery orifice lying in a plane making an acute angle with the axis of said delivery pipe, a plate spaced from said tip providing a chamber between said tip and said plate, said plate having delivery orifices therein disposed to deliver at an angle into the chamber between said tip and said plate, said plate being provided with a projection extending at right angles thereto and having a

longitudinal passage therein, said projection extending at an angle to said delivery pipe, a valve seat on the inner end of said projection, the plane of said valve seat extending at right angles to the axis of said delivery pipe, a valve coacting with said seat, a valve stem disposed through the inner end of said nozzle body extending parallel with said delivery pipe, spring means

10 normally holding said valve against said seat, and means for reciprocating said valve stem, all coacting substantially as described for the purpose specified.

In witness whereof, I have hereunto set my hand and seal in the presence of two witnesses. 15
